UNITED STATES PATENT OFFICE.

FRED I. ARNOLD, OF NEW YORK, N. Y., ASSIGNOR TO ROBERT L. McELROY, OF NEW YORK, N. Y.

CARBURETER.

1,307,107.

Specification of Letters Patent. Patented June 17, 1919.

Application filed November 11, 1916. Serial No. 130,708.

To all whom it may concern:

Be it known that I, FRED I. ARNOLD, a citizen of the United States, residing in New York, in the county of New York and State of New York, have invented certain new and useful Improvements in Carbureters, of which the following is a specification.

This invention relates to carbureters and among its main objects is to provide a carbureter that is compact, symmetrical and of such design as to permit of the air and gasoline connections being swiveled in any direction for convenient coupling and with the absence of any devices for control or adjustment that project in a manner to become injured and affect the operation of the carbureter; that is simple to install and can be quickly disassembled; that affords quick accessibility for cleaning; that has no parts moving with the motor; that can with great facility be quickly and accurately adjusted to produce a maximum efficiency, all of the air, gasoline and vapor passages having been scientifically determined as to size and form so that their relation to each other and as an entirety are productive of the best results possible to suit the various services that may be required of such carbureter; that embraces a highly efficient priming device; and that is absolutely secured from leakage of gasoline with its attendant dangers and disadvantages.

These and other features, capabilities and advantages of the invention will appear from the subjoined detail description of one specific embodiment thereof illustrated in the accompanying drawings in which—

Figure 1, is a side perspective view partially in section of my improved form of carbureter.

Fig. 2 is a view thereof looking in the same direction as in Fig. 1, taken in central longitudinal vertical section.

Fig. 3 is a top-plan view thereof.

Fig. 4 is a section along the line 4—4 of Figs. 1 and 2.

Fig. 5 is a section along the line 5—5 of Fig. 2.

Fig. 6 is a section along the line 6—6 of Fig. 2.

Fig. 7 is a detached elevational view of the cylindrical valve.

Fig. 8 is a fragmental sectional view illus-

trating another position of the cylindrical valve similar to the sectional view thereof illustrated in Fig. 4.

Figs. 9, 10 and 11 illustrate diagrammatically three different positions of the auxiliary air intake.

Figs. 12, 13 and 14 illustrate diagrammatically three different positions of the valve controlling the throttle outlet.

The embodiment illustrated comprises essentially four main portions which in construction are preferably castings and for convenience of description will be called the throttle outlet casting 15, the air intake casting 16, the Venturi tube casting 17, and the gasoline reservoir casting 18. On the casting 15 is mounted and secured the cover 19, below which is located the cylindrical valve 20 having anchored thereto the controlling fuel feed valve portion 21. The casting 16 is disposed between the castings 17 and 15 and is securely held therebetween; the casting 18, as shown; having an opening 22 at its lower end through which the lower end 23 of the casting 17, extends and to which lower end 23, the securing nut 24 is screw-threadedly connected, such nut 24 securely locking the casting 18 to the casting 17.

The casting 15 is provided with a chambered arm 25, the bore of which gradually enlarges in its outward extent terminating in the mouth 26 formed to be secured to the intake or manifold of an engine, the arm 25 at such mouth 26 being provided with the ears 27 having screw openings by means of which the casting 15 and thereby the carbureter itself may be anchored in place for operation.

The casting 15, Fig. 2, is furthermore provided with a hood portion 28, the arm 25 extending laterally therefrom. A cylindrical wall 29 extends downward from the upper inner periphery of the hood 28, to provide a mixing chamber for my carbureter, the wall 29, terminating in a flange 32. The wall 29 is preferably provided with an opening 30 adjacent to and communicating with the arm 25, the arm 25 being so connected to the wall 29 that communication is provided between the inside of the wall 29 and the passage through said arm 25 and no direct communication from the chamber formed between the wall 29 and hood 28 to the pas-

sage in said arm 25. The wall 29 is provided with another opening 31 which, in the present instance, is shown disposed diagrammatically opposite to the opening 30 and 5 forms a communication from the annular chamber formed between the hood 28 and wall 29 to the inside of said wall 29.

In the wall 29 and coöperating therewith is a cylindrical valve 20 which has a diminished cylindrical portion 33 extending upwardly through the central opening in the cover 19, a disk portion 34 extending laterally from the portion 33 and extending parallel to the cover 19, and having its outer 10 periphery fit snugly within the inner periphery of the hood 28. The valve 20 also has a cylindrical wall 35 extending downwardly from the disk portion 34, the lower edge of which wall 35 extends down into 15 the recess formed in the flange 32 and forms a tight fit therewith. The wall 35 has large openings 36 and 37 coöperating with the openings 30 and 31 respectively, the openings 36 and 37 being so disposed that they 20 will at the same time register with the openings 30 and 31 in open position. The openings 36 and 37 as to form and size have been scientifically determined to produce the best results possible, with the result that the 25 opening 36 is of the same width as the opening 30 at one side but is diminished at its other end, the diminished portion extending upwardly, while the opening 37 is of the same width as the opening 31 at one side but 30 is diminished at its other end, the diminished portion extending downwardly, the diminished portions of the openings 36 and 37 extending in the same direction so that the opening controlling the throttle outlet will 35 be diminished and enlarged simultaneously with the diminution and enlargement of the opening controlling the auxiliary air intake. To prevent the entire shutting off of the 40 opening to the throttle outlet, a plurality of small openings 38 are disposed in the cylindrical wall 35 (Figs. 12, 13 and 14) adjacent to the upwardly extending diminished end portion of the opening 36 and extending laterally in a substantially straight line and 45 50 in direction away from the opening 36, such openings 38 also being of varying size, disposed in such order that the largest is positioned adjacent to the upwardly extending diminished end portion of the opening 36 55 and the smallest remote therefrom. From the latter it will be seen that when the valve 20 is so actuated that both its openings 36 and 37 will be out of registration with the openings 30 and 31 the openings 38 will 60 register with the opening 30 and then permit the engine to suck in a limited amount of air and gasoline.

A solid stem portion 39 of the controlling fuel feed valve portion 21 extends outwardly 65 through the cylindrical portion 33 of the

valve portion 20, the stem portion 39 having a cup-shaped portion 40 disposed below the disk portion 34 and serving to receive one end of the coil spring 41, the other end being seated in the cup-shaped portion formed by 70 the collar 42 extending downwardly from the disk portion 34. By means of this spring 41 the lower tapered portion 43 of the valve portion 21 is held tightly in the tapering seat 44 in the casting 17, the collar 75 42 being connected with the top of 20, and with the peripheral wall thereof by the side-webs or partitions 42', shown in full lines in Figs. 4 and 8, and in dotted lines in Fig. 2. 80

The casting 17 has an upper funnel or conical shaped member 45, the upper enlarged portion 47 of which is connected to the flange 32 and the lower diminished portion 48 of which surrounds the series of perforations 46 formed in the valve portion 21 above the tapered portion 43. The funnel or conical shaped member 45 is supported by ribs 49 extending laterally therefrom to connect with the cup-shaped portion 50, conforming somewhat to the lower outer periphery of the funnel or conical shaped member 45 and terminating in the upper flange 51 to rest in the seat 52 formed in the lower periphery of the body 53 of the casting 16. Extending laterally from the cup-shaped portion 50 there is formed the hood-shaped member 54, the outer downwardly extending portion 55 of which is provided with an inner annular recess 56 in which 90 the upper edge 57 of the casting 18 rests. 95

The lower end of the cup-shaped portion 50 terminates in the portion 58 forming the annular chamber 66, which portion 58 continues downwardly into the cylindrical portion 59 in which the tapered seat 44 is formed, the seat 44 forming the upper part of the bore 62, the lower end of which is closed, the portion 59 however having an opening 60 in its side forming a communication between the bore 62 and the interior of the casing 18. 105

The valve portion 21 has a bore 61 extending upwardly from the lower end thereof to a point a little below the cup-shaped portion 110 40, the perforations 46 in the valve portion 21 forming communications between the bore 61 and the interior of the funnel or conical shaped member 45 as well as the interior of the cup-shaped portion 50. The lower end of the valve portion 21 is disposed a considerable distance above the lower end of the bore 62. The tapered portion 53 of the valve portion 21 is provided with an involute channel 63 (see Fig. 5) which is 115 adapted to register with the opening 60, the channel extending substantially one-half the periphery of the portion 43 and starting at one end at the outer periphery of the portion 43 and gradually increasing in 120 125 130

diameter to terminate in the opening 64 extending from the periphery of the portion 43 to the bore 61 thereof.

The tapered portion 43 is so formed relative to the tapered seat 44 that the perforation 46' formed in the valve portion 21 will be disposed substantially in alignment with the floor of the bowl or chamber 66, the other perforations 46 being disposed 10 a considerable distance above the same. This perforation 46' is so positioned that it will permit the formation of a low level of gasoline, say one-eighth of an inch, which when the engine is turned for starting will serve as the priming fuel on about the line *a—a* of Fig. 2.

The casting 16 comprises essentially a main air inlet 65 formed into an outwardly enlarging funnel, such inlet 65 being preferably disposed adjacent to the openings 31 in the wall member 29, and the body portion 53, the upper edge of which is provided with a seat 67 to receive the lower edge of the hood 28. From this it will be seen that the 25 air coming in through the inlet 65 may pass up through the hood 28 and in through the opening 31 when the valve 20 is properly positioned and in addition pass down between the cup-shaped portion 50 and the 30 funnel or conical shaped member 45 to the constricted end thereof and then upwardly into the expanded portion of the funnel or conical shaped member, sucking in gasoline through the perforations 46 in its upward 35 flight and then passing from the interior of the funnel or conical shaped member 45 into the interior of the chamber formed by the valve wall 35 and from there either through the opening 36 when the valve is so positioned or through the openings 38 into the 40 throttle outlet arm 25.

The casting 18 comprises essentially a reservoir casing 68 having a lateral extension 69 and a pet-cock 70 Fig. 5 disposed in its 45 bottom preferably at a distance removed from the extension 69 and the nut 24. The extension 69 is provided with a channeled stem guiding member 71 at its upper end, a needle valve seat 72 at its lower end, and below such seat 72 an extension 73 for connecting the extension 69 with the pipe connection of a suitable supply of gasoline. The extension 69 forms a constricted channel relative to the interior of the casing 68, the lower side 55 of which extension 69 is disposed a considerable distance above the lower side of the casing 68. In the extension 69 adjacent to the casing 68 there is disposed a shaft 74 on which is fixed the lever 75, one end of 60 which is fixed to the float 76, and the other end of which engages the slot 77 formed in the stem 78, the lower end of which stem 78 is formed into a point 79 to coöperate with the seat 72 and the upper end of which is 65 slidably mounted in the guiding member 71.

The float 76 is preferably composed of cork or like material and formed to surround the cylindrical portion 59 of the casting 17. The arrangement is such that the gasoline coming in from the extension 73 will fill up the 70 casing 68 to a point substantially in alignment with the top of the perforation 46' to which end the liquid will flow in through the opening 60 into the involute channel 63, through the opening 64 into the bore 61 75 and then through the opening 46' to the channel 66. The float 76 will be so arranged and adjusted relative to its control pin 78 that the tapered portion 79 will seat on the seat 72 when the liquid has risen to the 80 aforesaid level and thereby shut off any further entrance of liquid until the supply has been diminished to extend below such level.

For actuating the valve 20 and valve portion 21 the lever 80, Figs. 1, 2 and 3, is provided, which is screw-threadedly connected to the upper end of the stem portion 39 of the valve portion 21, to which such lever 80 may be locked by means of the bifurcated portion 81 of the lever 80 through which the 90 screw 82 extends.

On the cylindrical portion 33 of the valve 20 above the cover 19 is fixed the bracket 83 having the arms 84 and 85, the bracket 83 being adapted to be locked to the cylindrical 95 portion 33 by means of the bifurcated portion 86, Fig. 2, through which the screw 87 extends. The arms 84 and 85 are provided with the screws 88 and 89, Figs. 2 and 3, respectively at their ends, such screws 88 and 100 89 being also adapted to be locked in place by means of the bifurcated portions 90 and 91 through which the screws 92 and 93 respectively extend. The arms 84 and 85 are disposed at an angle a little more than ninety 105 degrees relative to each other with the arm 94 extending upwardly from the cover 19 disposed between them, and with the heads of the screws 88 and 89 extending away from the arm 94 so that the other ends of the 110 screws 88 and 89 will coöperate with the arm 94 to limit the movement of the bracket 83, the screws 88 and 89 being adjustable to produce the best results. To fix the valve portion 21 relative to the valve portion 20, the 115 arm 95 is provided which is screw-threadedly connected to the stem portion 39 and may be locked thereto by the coöperation of the bifurcated end 96 of the arm 94 and screw 97 which extends through said end 120 96. The outer end of the arm 95 is provided with an elongated portion 98 in which there is formed a curved slot 99 concentric with the path of movement of said arm 95 about said stem portion 39. Extending through the slot 99 there is provided a pin 100 which may be secured in any portion of said slot 99 by the nut 101. The lower end of the pin 100, Fig. 2, extends into the opening 102 formed in the arm 84 of the bracket 83. 130

Thus, it will be seen that the valve 20 may be locked to travel with the valve portion 21, and the involute channel 63 within a predetermined limited extent of movement adjusted relative to the openings 36 and 37, by means of the coöperation of the slot 99 and pin 100.

In the adjustment of the device, obviously the bracket 83 will be so positioned relative to the arm 94 and the screws 88 and 89 relative to said arm 94 that the openings 36 and 37 will register with the openings 30 and 31 to full open position and to full closed position in the two extreme positions of the bracket 83; and then the valve portion 21 positioned relative to the valve 20 so that its involute channel 63 will form a communication with the opening 60 when the openings 36 and 37 are in their extreme closed position, and also form a communication with the opening 60 when the openings 36 and 37 are in their extreme open position; and then the arm 95 so positioned relative to the stem 39 that it may adjust said involute channel 63 to afford greater or smaller communications from the casing 68 to the bore 61 relative to the extreme positions of the openings 36 and 37. The adjustment of the involute channel 63 by the arm 95 obviously need only be made when the carbureter is installed, and to suit various climatic conditions.

From the foregoing it is obvious that when the openings 36 and 37 register with the openings 30 and 31 to form the extreme open position, and the engine is started, the air will be sucked in through the intake 65 and at the start coöperate with the low level of the gasolene in the channel 66, and in its upward rapid movement through the funnel or conical shaped member 45 break up such liquid into spray, thereupon further mix with the auxiliary air coming in through the registered openings 30 and 36 in the valve 20, and then pass through the registered openings 37 and 31 through the throttle outlet 25 into the engine, and such action continue with the exception that with the increased speed of the engine the liquid traveling up the bore 61 will be sucked up to the openings 46 and travel through them into the funnel or conical shaped member 45 to mix with the incoming air and be passed into the engine.

On the other hand, when the valve 20 is so positioned that the opening 30 is completely shut off, the air and gasolene may still travel up through the funnel or conical shaped member into the valve 20 and from there through the openings 38 through the opening 31 into the throttle outlet 25 and then into the engine.

Figs. 9 and 12 show the respective positions of the openings 36 and 37 when the opening 31 is completely shut off and passage permitted through the opening 30 only

through the openings 38; Figs. 10 and 13 show the respective positions of the openings 36 and 37 when the opening 31 is partially closed and passage through the opening 30 permitted by means of part of the opening 36 and only two of the openings 38; and Figs. 11 and 14 show the respective positions of the openings 36 and 37 when the openings 30 and 31 are completely opened.

A particular feature of the present construction is the arrangement whereby both the valve 20 and valve portion 21 are secured to the cover 19 which is secured to the casting 15 by two screws 105 and 106, Figs. 1 and 3, and thus when it is desired to clean the channel 66 or the valve 20, it is only necessary to remove the screws 105 and 106, thereby removing the cover 19 and with it the valve 20 and valve portion 21.

It is obvious that various changes and modifications may be made to the details of construction without departing from the scope of my invention as defined by the claims.

I claim:—

1. A carbureter comprising a throttle outlet, a mixing chamber, a fuel reservoir, a cone shaped hood disposed between said fuel reservoir and mixing chamber, the enlarged end of said hood being disposed adjacent to the mixing chamber, there being a communication from said mixing chamber to said throttle outlet, an air intake, there being a communication from said air intake about the outer surface of said hood to the constricted end thereof and then into said hood, a stem extending through the mixing chamber, a chambered extension at the lower end of said stem extending through the hood, a chambered member extending into the reservoir, the chambered extension being disposed therein there being a communication from said reservoir through said chambered member into said chambered extension, there being communications from said chambered extension to the interior of said hood so that the air passage through said hood will draw the fuel from said reservoir through the communications in said extension up through said hood to said mixing chamber, the extension having a tapered lower portion, the upper chambered portion of the chambered member being tapered to receive the lower tapered portion of the chambered extension, and means for normally maintaining said lower tapered portion securely in the chambered portion of said chambered member.

2. A carbureter comprising a throttle outlet, a mixing chamber, a fuel reservoir, a funnel or conical shaped member between said fuel reservoir and said mixing chamber, there being a communication from said mixing chamber to said throttle outlet, an air intake, there being a communication from

5 said air intake direct to said mixing chamber, there being a communication from said air intake to the constricted end of said funnel or conical shaped member, a cylindrical valve in said mixing chamber having openings to coöperate respectively with the communication from said air intake and with the communication to said throttle outlet, the cylindrical valve being operable to
10 simultaneously shut off the direct communication from said air intake to said mixing chamber and to vary the size of communication from said mixing chamber to said throttle outlet, a stem extending through the
15 mixing chamber, a chambered extension at the lower end of said stem extending through the funnel or conical shaped member, a chambered member extending into the reservoir, the chambered extension being disposed therein, there being a communication from said reservoir through said chambered member into said chambered extension, there being communications from said chambered extension to the interior of the said funnel
20 or conical shaped member so that the air passing through said funnel or conical shaped member will draw the fuel from said reservoir through the communications in said extension up through said funnel or
25 conical shaped member to said mixing chamber, a spring abutment on said stem, and a spring strained between said cylindrical valve and said spring abutment for normally maintaining the lower tapered portion
30 conical shaped member to said mixing chamber, a spring abutment on said stem, and a spring strained between said cylindrical valve and said spring abutment for normally maintaining the lower tapered portion
35 securely in the chambered portion of said chambered member.

3. A carbureter comprising a throttle outlet, a mixing chamber, a fuel reservoir, a funnel or conical shaped member between said fuel reservoir and said mixing chamber, there being a communication from said mixing chamber to said throttle outlet, an air intake, there being a communication from said air intake direct to said mixing chamber, there being a communication from said air intake to the constricted end of said funnel or conical shaped member, a cylindrical valve in said mixing chamber having openings to coöperate respectively with the communication from said air intake and with the communication to said throttle outlet, a stem extending through the mixing chamber, a chambered extension at the lower end of said stem extending through the funnel or conical shaped member, a chambered member extending into the reservoir, the chambered extension being disposed therein, there being a communication from said reservoir through said chambered member into said chambered extension, there being communications from said chambered extension to the interior of the said funnel or conical shaped member so that the air passing through said funnel or conical shaped member will draw the fuel from said reservoir through the

communications in said extension up through said funnel or conical shaped member to said mixing chamber, a bracket fixed to said cylindrical valve and disposed above the same, an arm for coöperating with said bracket to define the limit of movement of said cylindrical valve, a second arm fixed to said stem, and a pin operatively connecting said second arm with said bracket so that the stem and cylindrical valve will operate together. 70 75

4. A carbureter comprising a throttle outlet, a mixing chamber, a fuel reservoir, a funnel or conical shaped member between said fuel reservoir and said mixing chamber, there being a communication from said mixing chamber to said throttle outlet, an air intake, there being a communication from said air intake direct to said mixing chamber, there being a communication from said air intake to the constricted end of said funnel or conical shaped member, a cylindrical valve in said mixing chamber having openings to coöperate respectively with the communication from said air intake and with the communication to said throttle outlet, the cylindrical valve being operable to simultaneously shut off the direct communication from said air intake to said mixing chamber and to vary the size of communication from said mixing chamber to said throttle outlet, a stem extending through the mixing chamber, a chambered extension at the lower end of said stem extending through the funnel or conical shaped member, a chambered member extending into the reservoir, the chambered extension being disposed therein, there being a port from said reservoir through said chambered member, there being a second port from the chambered member into said chambered extension, and there being an involute channel along the outer periphery of said chambered extension terminating at one end at the second port, the involute channel serving as the controlling passage from the first port to said second port. 100 105 110

5. A carbureter comprising a throttle outlet, a mixing chamber, a fuel reservoir, a funnel or conical shaped member between said fuel reservoir and said mixing chamber, there being a communication from said mixing chamber to said throttle outlet, an air intake, there being a communication from said air intake direct to said mixing chamber, there being a communication from said air intake to the constricted end of said funnel or conical shaped member, a cylindrical valve in said mixing chamber having openings to coöperate respectively with the communication from said air intake and with the communication to said throttle outlet, the cylindrical valve being operable to simultaneously shut off the direct communication from said air intake to said mixing chamber 130

- chamber and to vary the size of communication from said mixing chamber to said throttle outlet, a stem extending through the mixing chamber, a chambered extension at the 5 lower end of said stem extending through the funnel or conical shaped member, a chambered member extending into the reservoir, the chambered extension being disposed therein, there being a port from said reservoir through said chambered member, there being a second port from the chambered member into said chambered extension, there being an involute channel along the outer periphery of said chambered extension terminating at one end at the second port, the involute channel serving as the controlling 10 passage from the first port to said second port, means for operatively connecting said stem with said cylindrical valve, and means connected to said stem for controlling the 15 involute passage whereby the communications from said air intake to said mixing chamber and from said mixing chamber to said throttle outlet will also be controlled.
- 20 6. A carbureter comprising a throttle outlet, a mixing chamber, a fuel reservoir, a funnel or conical shaped member between said fuel reservoir and said mixing chamber, there being a communication from said mixing chamber to said throttle outlet, an air intake, there being a communication from said air intake direct to said mixing chamber, there being a communication from said air intake to the constricted end of said 25 funnel or conical shaped member, a cylindrical valve in said mixing chamber having openings to coöperate respectively with the communication from said air intake and with the communication to said throttle outlet, the cylindrical valve being operable to simultaneously shut off the direct communication from said air intake to said mixing chamber and to vary the size of communication from said mixing chamber to 30 said throttle outlet, a stem extending through the mixing chamber, a chambered extension at the lower end of said stem extending through the funnel or conical shaped member, a chambered member extending into the reservoir, the chambered extension being disposed therein, there being a port from said reservoir through said chambered member into said chambered extension, there being communications from said chambered extension to the interior of the said Venturi tube so that the air passing from said funnel or conical shaped member will draw the fuel from said reservoir through the communications in said extension up through said funnel or conical shaped member to said mixing chamber, a bracket fixed to said cylindrical valve and disposed above the same, an arm for coöperating with said bracket to define the limit of movement of said cylindrical valve, a second arm fixed to said stem, a pin operatively connecting said second arm with said bracket so that the stem and cylindrical valve will operate together, a cover for said mixing chamber, the cylindrical valve being anchored to said cover, and means for securing said cover to said mixing chamber, the removal of said securing means permitting the removal of the cover and with it the cylindrical valve and stem for the purpose of cleaning.
- 35 7. A carbureter comprising a throttle outlet, a mixing chamber, a fuel reservoir, a funnel or conical shaped member between said fuel reservoir and said mixing chamber, there being a communication from said air intake direct to said mixing chamber, there being a communication from said air intake to the constricted end of said funnel or conical shaped member, a cylindrical valve in said mixing chamber having openings to coöperate respectively with the communication from said air intake and with the communication to said throttle outlet, the cylindrical valve being operable to simultaneously shut off the direct communication from said air intake to said mixing chamber and to vary the size of communication from said mixing chamber to 40 said throttle outlet, a stem extending through the mixing chamber, a chambered extension at the lower end of said stem extending through the funnel or conical shaped member, a chambered member extending into the reservoir, the chambered extension being disposed therein, there being a port from said reservoir through said chambered member into said chambered extension, there being an involute channel along the outer periphery of said chambered extension terminating at one end at the second port, the involute channel serving as the controlling passage from the first 45 port to said second port, a bracket fixed to said cylindrical valve and disposed above the same, an arm for coöperating with said bracket to define the limit of movement of said cylindrical valve, a second arm fixed to said stem, a pin operatively connecting said second arm with said bracket so that the stem and cylindrical valve will operate together, a cover for said mixing chamber, the cylindrical valve being anchored to said cover, and means for securing said cover to said mixing chamber, the removal of said securing means permitting the removal of the cover and with it the cylindrical valve and stem for the purpose of cleaning.
- 50 8. A carbureter embracing four main castings, one of said castings forming a throttle outlet and a mixing chamber, the second casting forming the air intake and air passages, the third casting forming the Venturi tube and a cup shaped member, and the fourth casting forming the fuel reservoir, the third casting being secured to said first casting and anchoring between said first casting and said third casting the second casting, means for securing the fourth casting to the third casting, the cup shaped member forming the cover for said fuel
